UNITED STATES PATENT OFFICE.

PHILIP K. EATON, OF OLYMPIA, WASHINGTON.

METHOD OF MARKING X-RAY FILMS.

Application filed May 9, 1927. Serial No. 189,953.

It is desirable in connection with photographs made by X-ray apparatus to have the film carry suitable words or figures or other marks which serve, either by themselves or in connection with other data, to indicate the time when the photograph was taken, the reason for taking it, etc. Such data is particularly desirable in connection with personal injury cases and it is, of course, very important that the record on the film itself, and that will be transferred to the prints made from it, be not only as permanent as the photograph on the film of the injured parts, but as full and complete as possible. However, it is common practice in large institutions that have to do with personal injuries to merely photograph on the film, simultaneously with the taking of the photograph of the injured part, a number that corresponds to the number appearing on a written record of the patient's case,—such number being made to appear on the film by the use of figures cut, after the manner of a stencil, in a lead plate which rests upon the holder in which the film is located. This method of identifying an X-ray film with the hospital or other record that is kept of a patient is objectionable for a variety of reasons which it does not seem necessary to here set forth as such objections are well recognized by hospital attendants, and also by lawyers in their trial of personal injury cases.

It is the object of my invention to provide a method by which, and by the employment of very simple means, a quite comprehensive record may be photographed upon the film so that upon such film, and, of course, upon all prints made from it, there will appear in addition to the number given to a patient's case, his name, address, date of the photograph, name of the hospital, the surgeon, etc. Briefly, and rather broadly stated, I accomplish this by writing on a piece of paper the data that it is desired shall appear on the film, then placing such paper against the film with that surface of the paper on which is the writing lying in contact with the film, and thereafter, with said film and piece of paper enclosed in an ordinary double screen holder, subjecting the film in the usual manner to the action of the X-ray, whereby the film will have produced thereon not only the showing of the injured member or other article that is interposed between the holder and the source from which the ray ema-

nates, but will also reproduce on the film the written matter that is on said piece of paper. It is obvious, however, that if a piece of paper is arranged with reference to the film so that the surface of the paper on which the writing has been made in the usual manner lies directly against the upper surface of the film the writing will be transferred to the film in a reversed position, and, furthermore, unless the exposure to the ray is of shorter duration than is usually desired, the reproduction of the writing on the film is apt to be somewhat blurred and therefore not wholly satisfactory.

To ensure a more perfect identifying record of the written matter on the film I simultaneously produce a plurality of copies of the written matter, and arrange two of them on opposite sides of the film with the written matter on each in direct contact with a surface of the film, and with one of such copies reversed relatively to the other. As it is, of course, necessary that the two duplicate writings be exactly opposite or in registry one with the other, it will be evident that with the written matter in each instance faced against the film one of the writings must be reversed as above stated. In putting into practice my improved method I employ a sheet of carbon paper so folded over upon itself that the carbon or impression surface is outermost, and this folded carbon sheet is then arranged between a piece of writing paper that is folded over upon the folded carbon sheet. With these two papers so arranged it will be seen that any writing made upon the outer surface of one leaf of the writing paper will, by the action of the carbon, be reproduced in reverse on the inner surface of said leaf and also in the form of a perfect duplicate on the inner surface of the other leaf of the writing paper, and it will be these two carbon writings,—one in reverse and the other an absolute duplicate of the original,—that will, when the carbon sheet is separated from the writing paper and the latter placed with its two leaves on opposite sides of the film, come in contact, respectively, with the two surfaces of the film.

Obviously, the simultaneous making of the two writings,—one of which is reversed with respect to the other,—which are arranged to lie in contact with the surface of the film, as stated, might be produced by employing an unfolded sheet of paper that was carbonized

on both of its sides, but as sheets carbonized only on one side are in general use, and when folded as described, are perfectly satisfactory for producing the desired result, I prefer to use such a folded sheet.

In the accompanying drawing are shown the means employed by me for practicing the improved method.

Fig. 1 is a perspective view of a piece of paper folded once upon itself, and upon which the matter that is subsequently to appear upon a film is to be written, and showing also a carbon sheet inserted between the two leaves formed by the folding of the paper.

Fig. 2 is a perspective view showing a strip that has been detached from the piece of paper after the desired written matter has been placed thereon, and preparatory to placing such strip in place on a film.

Fig. 3 is a perspective view showing a portion of an X-ray film with the paper strip of Fig. 2 partly in place thereon; and

Fig. 4 is a cross-section through an ordinary film holder with a film therein and the strip of paper that is shown in Fig. 2 lying in close contact with both surfaces of the film.

In the drawing the thickness of the paper and the carbon sheet is, as will be understood, very considerably exaggerated.

Referring to the several figures of the drawing:—5 indicates a sheet of writing paper folded upon itself centrally so as to form two leaves, and across the paper are preferably a series of lines of perforations, as clearly indicated in Fig. 1, whereby strips such as shown in Fig. 2 are adapted to be easily detached. Each of the divisions of the paper 5 made by these lines of perforations is to be wide enough to have written or printed thereon by a pen, pencil or typewriter sufficient matter to constitute quite a full identifying record and at the same time not be so wide as to interfere with the production on the film of the required showing of the injured member of a patient, or such other thing as may be the subject of investigation. Such a strip will ordinarily be placed in position on a film near one of the end margins of a film, as in Fig. 3. The detached strip of paper shown in Figs. 2 and 3 is marked by the reference character 5^a.

55 The carbon sheet that has been referred to and that is shown in Fig. 1 is indicated by 6. It is folded upon itself to correspond to and lie within the folded paper 5, and as indicated it is folded so as to bring its carbon surface outward so that such surface will lie against the inner surfaces of the two leaves of the paper 5. The result will be, of course, that any marking made upon an outer surface of one of those leaves will 65 be reproduced upon both of the inner sur-

faces of such leaves, the reproduction upon the leaf that the user writes upon being reversed while the reproduction upon the other one will be a perfect duplicate of the original.

7 indicates an ordinary X-ray film, and, as clearly indicated by the strip 5^a that is partially in position on a film in Fig. 3, the two reproductions of the matter that has been put upon the strip will lie respectively opposite the upper and lower surfaces of the film, and when such strip is held pressed closely to the film as will be the case when locked in a holder, as in Fig. 4, such two reproductions will be in registry with each other. The result of this arrangement is that the film is shielded by the strip and particularly by the registering printed matter that has been placed thereon so that when the film is subjected to the action of the X-ray the desired identifying matter will appear upon the film to the same extent as the showing made thereon of the member or thing that is at the same time resting on the outer wall of the film holder.

8 indicates the main or body portion of an ordinary double screen film-holder or cassette, between the top wall of which and a hinged cover or closure member 9 the film 7 with a marked strip 5^a arranged thereon as described is adapted to be tightly held. 10 and 11 indicate the usual intensifying screens that are attached respectively to the opposed faces of said upper wall and closure member.

It is frequently necessary to place the film-holder in various positions other than horizontal while the X-ray is directed upon it, but at whatever angle the holder may be placed it is evident that the strip 5^a will always remain in place and hence ensure the desired marking of the film, which is a very considerable advantage over the use of marking means that rest upon the outer surface of the film-holder.

What I claim as new and desire to secure by Letters Patent is:

1. The method of marking an X-ray film which consists in placing against the two surfaces of an X-ray film a paper which has two pieces of written matter thereon, said written matters being placed directly opposite each other and being the same in all respects except that one is reversed with respect to the other, each of such written matters lying in direct contact with one surface of the film, and then subjecting the film to the action of the X-ray.

2. The method of marking an X-ray film for identification, which consists in writing upon an outer surface of a piece of paper that is folded upon itself and has between the two leaves that are formed by the folding of the paper a carbon sheet that is also folded to present its carbonized surface to

the inner surfaces of the two leaves of the said folded paper, whereby the writing will be reproduced in reverse on the inner surface of the leaf of the piece of the paper that has been written upon and in duplicate upon the inner surface of the other leaf, then separating the said paper from the car-

bon sheet and placing it on the film with the surfaces that bear said reproductions in contact with the opposite surfaces of the film, and then subjecting the film to the action of the X-ray.

PHILIP K. EATON.
